UNITED STATES PATENT OFFICE.

OSCAR W. BROBERG, OF CLEVELAND, OHIO; MABEL BROBERG ADMINISTRATRIX OF
SAID OSCAR W. BROBERG, DECEASED.

FUEL ECONOMIZER FOR INTERNAL-COMBUSTION ENGINES.

Application filed August 30, 1922. Serial No. 585,299.

To all whom it may concern:

Be it known that I, OSCAR W. BROBERG, a resident of the city of Cleveland, in the county of Cuyahoga and State of Ohio, and a citizen of the United States, have invented certain new and useful Improvements in Fuel Economizers for Internal-Combustion Engines, of which the following is a specification.

10 This invention relates to an improved device for economizing fuel in the use of internal combustion engines, and has for its objects aside from that mentioned, to provide such a device which is automatically controlled from the main throttle rod of the engine, so that a saving is effected in the quantity of liquid fuel used, a saving in the amount of lubricating oil required, and a partial refining of the latter oil effected.

15 20 A further object of my invention is to prevent the fuel gases accumulating in the intake manifold when the engine is stopped, from flowing back, after liquefying, into the carburettor and flooding the latter, thus making it difficult to start the engine thereafter. My improved device avoids such flooding of the carburettor.

A further object is to carry off the hot vapors from the gear and crank cases and feed them into the intake manifold with the usual fuel gas mixture, thus serving to further heat such mixture and also cool the said lubricating oil of the cases.

It is a special object of my improvement to make the use of my economizer automatic, so that it is connected with the manifold when the engine is running but disconnected at all times when the latter is idle. This arises from the fact that the use of the improvement does not depend on the control of the operator, but is so connected to the main throttle rod, that it is opened and closed therewith. It is therefore in use when it is needed.

45 A still further advantage results from my improvement in that it may be fitted to any internal combustion engine and that without buying new parts other than this device itself.

50 Other objects will appear as the description proceeds.

The invention consists essentially of the arrangements and construction of parts herein described, and the scope of which will be pointed out in the claims following,

it being understood that changes may be made in the structure disclosed within the scope of said claims.

In the drawings, in which similar reference characters indicate corresponding parts in the several views,

Figure 1 is a fragmentary side elevation of an internal combustion engine with the improvement applied thereto,

Figure 2 is a plan view of the carburettor and my device with related parts,

Figure 3 is a view in cross section taken on the line 3—3 of Fig. 2, and

Figure 4 is a sectional view as seen in the plane indicated by the line 4—4 of Fig. 3.

My improved device is shown in the drawings in connection with a conventional type of vehicle engine provided with the usual crank case A, carburettor B, intake manifold C, and exhaust manifold D. In Fig. 2 is also shown in plan the usual parts 1, 2 and 3 representing conventionally the throttle valve stem, lever and rod, respectively.

My improved device is applied between the carburettor and the intake manifold. This is emphasized, for the reason that there have been a number of attempts in the past to feed hot vapors into the rear end of the carburettor thus passing therethrough in their course to the said manifold. I have found such connection to be undesirable for my purpose as will be later explained.

My economizer comprises a thin plate 4 which is nearly rectangular in outline, a circular aperture 5 intersecting the plate near its center, and tubular elements 6 and 7 being secured to the side and end of the plate respectively. In some cases, it may be found desirable to make these tubes integral with the plate, but I have shown them welded or brazed thereto. In any event, the interior of the tubes are made to communicate by an opening 6a.

The aperture 5 has communication with the tube 6 by means of a plurality of parallel small pipes 8, so that gases in tube 7 will find ready entrance into the aperture 5. The lower end of the tube 7 has a substantially cylindrical bore 9 leading to the opening 6a. About mid-way of its length part 7 has an inner nipple 10 separated from the outer wall by an annular socket 11 to receive any liquid that might accumulate

in the tube, and the upper surface of the part 10 is smooth and flat to receive a valve plunger at 15 and thus serve as an auxiliary throttle.

- 5 The upper end of the tube 7 is an inner threaded part 12 which is shown as a separate part seated in the remainder of the tube for purposes of manufacture, but which may be made integral if desired.
- 10 The reduced part 10^a serves to conduct the sections of 7 together. The valve plunger part 14 is fitted to engage the threaded part 12 at 13 so that as the part 14 is rotated it opens the part 9 into the space enclosing the reduced end of the plunger, or closes it at 15, as before explained. The part 14 therefore serves as a throttle.

15 The said throttle member 14 is actuated by a lever 17 which is adjustably secured 20 to said member by a screw 18, shown here as in the plane of the lever 17 but which obviously may be positioned in the plane of the member 14. Said lever 17 is provided with a plurality of apertures 19 for adjustably securing therein the end of an actuating link 21 and which latter is in turn fixed to the main throttle rod 3 by a clamp 22, as shown in Fig. 2.

25 The reciprocation of the rod 3 (usually operated manually) therefore opens or closes the entrance of vapors into the tube part 9, by the intermediacy of parts 22, 21, 17, 14 and 15.

30 Mounting:—As shown clearly in Fig. 2 of the drawings, the conventional manner of connecting the front end of the carburettor with the intake manifold is to provide an external flange about the tubular opening from each, and clamp these flanges together by suitable coupling bolts. This construction is found on all engines of this type. To mount my economizer in position, these aforesaid flanges are separated by withdrawing said bolts, and then inserting 35 the plate 4 of my device between said flanges, so that the opening 5 shall be in exact alinement with said carburettor and manifold tubes, the said opening being of such size as to very accurately register with the other parts, as before explained. See 40 Figs. 1 and 2. Longer bolts will then be substituted for those before employed and will be inserted through the holes 16 of the plate 4, and the clamp 22 fitted onto the link or rod 3. All fuel gases from the carburettor will now pass through the opening 5 and thence to the intake. When the engine stops running, due to the throttle 1 being closed, the vapors in said intake manifold after cooling, will flow back toward the carburettor, and in normal and ordinary conditions will flow back into the carburettor, flooding it and choking it, often causing difficulty in starting the engine again, especially in cold seasons. But with my de-

vice in position, such liquefied vapors cannot reach the carburettor, but in passing through the opening 5 they drop down the pipes 8 into the tube 6, remaining there until the main throttle is again opened to 70 start the engine. Then, as soon as the engine starts, as will now be done readily as the carburettor is free of liquid either thin or plastic, a vacuum in the manifold causes pressure in the tubes 6 and 7 to 75 force the accumulated liquid there up into the pipes 8 and thence into the manifold and cylinders to add to the ordinary fuel.

Extending laterally and perpendicularly from the mid-point of tube 7, is a tube 20 80 which serves to feed the vapors from the casings to this auxiliary throttle space, and when the latter is open, to the parts 9, 6, 8, 5, and thence to the manifold. This tube 20 is connected by suitable fittings to the 85 casings, either to the gear case at 23, as here shown, or to the breather pipe itself, as is well understood, or even by withdrawing the cap of the "breather" and adding another section into which the tube 20 may 90 be detachably secured. It is immaterial, so far as my invention is concerned, how the said tube is connected with the cases or either of them. The essential feature is that the new device here shown shall have 95 communication with the upper portion of one of the casings so that the hot vapors therein may be conducted to the manifold by connection intermediate the manifold C and carburettor B. This connection is at 100 the extreme lower end of the part C, so that the device will receive all moisture flowing down from part C.

As a further means for making certain the flow of liquid from opening 5 into the tube 105 part 6, the periphery of the said circle 5 has an annular groove 24 which serves as a trough at its lower arc nearest the pipes 8 to direct the liquid into the pipes. See Fig. 3. While liquid might flow over a 110 smooth surface of such opening into the carburettor, it is highly improbable that it will flow over such a trough-shaped groove as leads to these pipes.

Operation:—The plate 4 having been 115 mounted between the flanges of the joint at the front end of the carburettor with tube 6 horizontal and below the opening 5, and the clamp fixed to the rod 3, opening the main throttle in the usual manner will turn 120 the stem 14 and also open the throttle leading to tubes 6 and 7. The tube 20 is connected to a suitable opening in some high level of the crank case or an extension therefrom, and hot vapors will be drawn into 125 pipes 8 whenever the main throttle is open—the engine running. Such drawing off of the hot vapors from the lubricating oils, not only enriches the fuel oil mixture but also refines the oil from which 130

they are drawn, and economizes on the fuel cost. Such drawing off of the vapors from that source also tends to cool the case oil and therefore saves the life of the gears.

5 It is to be noted that the mounting of this plate and its related parts requires no additional machining of old parts, and that when for any reason it should be desirable to remove the device temporarily, it can 10 be easily done and the parts connected as before. This provides readily for repair of the parts. Or, if it should be desired to throw the attachment out of commission temporarily, it is only necessary to remove 15 the clamp 22 from the rod 3, and fix the stem in tightened relation so as to hold the valve 15 closed. This can be done without removing the plate.

I do not desire to limit myself to the 20 exact form of the parts here illustrated or to the particular structure described, but desire to claim any modifications possible within the spirit and scope of the invention.

What I claim as new and desire to secure 25 by Letters Patent is:

1. In an internal combustion engine, a valve mechanism adapted to be inserted between the intake manifold and carbureter, comprising a plate having an aperture 30 therethrough, the peripheral edge of the aperture having an annular groove serving as a trough at its lower portion, a tube secured to the lower edge of said plate and in the plane of the latter and pipes connecting said tube and trough, whereby liquefied 35 gases flowing back from the intake will flow into the trough, down the pipes and thence into the edge tube, a control valve for directing the entrance of gases into said tube 40 and thence to said pipes, and means for controlling said valve, substantially as set forth.

2. In a device for economizing fuel of internal combustion engines, a flat plate having 45 a transverse aperture near its center and smaller apertures for securing the device in position between the carbureter and intake manifold, a pair of tubes, one of which is mounted on an edge of the plate 50 and the other on another edge at right angles to the first, the tubes communicating with each other and one of them having means for communicating with the first mentioned aperture, and the other having a threaded 55 opening and a shoulder therebelow spaced from the outer wall of the tube, a threaded stem engaging said threaded opening and having a valve element for resting on said 60 shoulder when the stem is secured into the opening, a tube leading to said space, and actuating means for said valve stem, substantially set forth.

3. In an internal combustion engine having 65 a carbureter and intake manifold detachably connected together, and gear and crank

cases, a fuel economizing mechanism comprising a flat plate adapted to be secured between said carbureter and manifold and having a transverse opening therethrough in alignment with the axes of said carbureter 70 and manifold, tubular parts secured to intersecting edges of said plate, one of said tubes being below said opening, parallel pipes within said plate and leading from said lower tube up into the opening, and the 75 other tubular part having a reduced bore at one end communicating with the first tube, a larger internally threaded opening at the other, thus providing a shoulder between the two openings, and an intermediate 80 enlarged space between the two openings, a stem having a plunger at one end adapted to engage the shoulder to close the reduced opening, and a threaded part to register with the threaded opening, a tube intersecting the plane of the plate and communicating with said intermediate space, a lever secured to said stem for actuating the same, and means for connecting said last mentioned tube with the case, substantially as 85 set forth.

4. In an internal combustion engine, the combination with the crank case having a suitable port, an intake manifold, a carbureter, carbureter valve and control rod 95 therefor, of fuel economizer mechanism adapted to be inserted between the lower end of the intake manifold and the carbureter comprising an apertured plate having a tube parallel with and fixed to the lower edge of said plate and pipes within said plate establishing communication between the said aperture and tube, valve means for controlling the entrance of fluids into said tube, means for conducting fluids from said 100 port to said valve means, and means connected with said control rod for actuating said valve means, substantially as set forth.

5. In an internal combustion engine, the combination with the intake manifold and carbureter detachably connected together adjacent the combustion end of the carbureter, of means including a plate inserted 110 between the carbureter and manifold and having a socket below the level of the carbureter for receiving therein liquids flowing back from the manifold, thereby preventing flooding of the carbureter when the engine is not running, and means for directing hot vapors from the crank case to said liquid receiving means to vaporize and expel said 115 back-flowing liquids into the manifold when the engine is running, substantially as set forth.

6. A fuel economizing mechanism for internal combustion engines comprising a secondary throttle means, a flat plate secured between the carbureter and the intake manifold having a tube on one lower edge thereof and parallel therewith, an aperture 125

transverse of said plate near its center and small pipes entering said aperture and communicating with said tube, the latter having communication with said throttle means, and 5 means controlled automatically by the main throttle mechanism of the engine for in turn controlling the said secondary throttle means, substantially as set forth.

7. In an internal combustion engine, the 10 combination with the crank case, intake manifold and carbureter, of means inserted between the manifold and carbureter for

catching the back-flowing liquid from the manifold, said means including an apertured plate and pipes within the plate leading 15 from its lower edge to said aperture and means connected with said crank case for receiving hot vapors from the latter and directing them into said pipes for vaporizing said liquid and returning them to the said 20 manifold, substantially as set forth.

In testimony whereof I hereunto affix my signature.

OSCAR W. BROBERG.
